UNITED STATES PATENT OFFICE.

GEORGE E. MARLATT, OF PASADENA, CALIFORNIA.

SLUG-CASTING MOLD FOR TYPOGRAPHICAL MACHINES.

Application filed November 13, 1926. Serial No. 148,305.

My invention relates to means whereby the mold slot in which the slug of printing type is cast may be adjusted to produce a slug of any desired length or thickness without employing removable and substitutable liners as is the common practice in machines of the linotype class. My objective is to provide a mold of dependable construction which may be quickly and accurately adjusted to selected points of thickness and ems or fractional ems of length without the liability of the molten metal entering between the movable parts in the casting operation. A further and contributing object is to provide means whereby such a mold will be continuously lubricated not only as to the movable parts but with regard to the casting slot in order that the slug may be readily ejected therefrom. In the accompanying drawings—

Fig. 1 represents a rotatable mold carrier having thereon two molds differently adjusted both as to length and thickness, and two other molds with portions omitted in order to show the construction of certain other portions. This view also shows a system of lubricant cells and ducts by means of which the lubricant is flowed from the mold in operative position to those in non-operative position.

Fig. 2 is a section through the center of Fig. 1.

Fig. 3 is a view of the principal movable portion of the mold as it appears in Fig. 1, and Fig. 4 is an edge view thereof.

Figs. 5 and 6 are views of a longitudinally movable end-closing member corresponding in function to the usual substitutable mold liners of various lengths.

Fig. 7 shows a right-hand end-closing member which retains a constant position relative to the length of the mold slot but is adjustable according to the thickness thereof, hence corresponds in function to the usual right-hand mold liners of various thicknesses, but constant length.

When employed in connection with the usual rotatable carrier as in linotype machines, the conditions are such that the longitudinally-adjustable member of the mold must not extend beyond the edge of the disc-

carrier. Since this would be unavoidable if a single mold were made adjustable from minimum to maximum of established measurements, I therefore provide four molds each having a limited length adjustment. But each of the four molds has the full range of adjustment for slug thickness, therefore the four molds will provide for a slug of any thickness or length within the usual limitations. In fact, in the proportions illustrated, three molds will provide the usual range of adjustment, and the fourth may be a duplicate of one of the others or have an adjustment overlapping in range the maximum of one mold and minimum of another. Except for the fact that the movable end-closing member I differs in length in the several molds, a description of any one mold will apply to the others.

The constant floor *a* of each mold is one edge of a square carrier-center *A*. The four molds are therefore immovable relative to each other and to the center of the carrier, which is a distinct improvement over the usual method for the reason that each mold is insured accurate alinement relative to the usual trimming knives when in slug-ejecting position and relative to the usual pot-mouth when in casting position. The square disc-center *A* is grooved as at *A*¹ across each corner to receive projections *B*¹ from the inner edge of an internal flange *B*, and pins *B*² serve to secure the two members *A* and *B* relatively integral and immovable. To the flange *B* is secured a stiffening rim *C* which may have the usual gear teeth if the carrier is of the gear-driven type. The web *B* seats into an annular shoulder *C*¹ of the rim *C*, and binding strips or bars *D* serve to hold the two members securely joined together, these strips being seated in grooves *B*³ in the web *B* and continuations *C*² thereof in the rim *C*. The bars *D* are secured in their grooves by means of screws *D*¹ and project from the face of the carrier as banking elements against which the mold adjusting members are stopped in selected positions. One of these adjusting members *E* serves to lock the mold cap *G* according to the lengthwise adjustment of the mold slot *S*, and for this purpose has teeth *E*¹ cut in

opposing directions at its opposite ends. These teeth engage similar teeth on the bar D and the adjusting member E is thus held longitudinally immovable in either direction except when manually lifted against the tension of a spring H. This spring H is secured by means of a pin H¹ to a projection G¹ from the mold cap G. The projection G¹ enters a notch E² in the locking member E, hence the mold cap and locking member therefor must move together longitudinally and be locked together in a selected position. The projection G¹ is movable longitudinally and transversely in an opening B⁴ through the web B, its transverse movement being incident to the thickness adjustment of the mold slot.

The mold cap G is channeled (G⁵) to fit the carrier web B and is thus held laterally immovable when under lateral pressure during the slug casting and ejecting operations, or at any other time. The front wall of the channeled mold cap is provided with a recess G² which embraces the front edge of the length-adjusting and end-closing member I; hence when the locking member E is raised out of engagement with the bar D against the resistance of the spring H and moved longitudinally, the end-closing member I moves with the mold cap a corresponding distance and a length adjustment of the mold slot is accomplished. For this purpose the teeth D² and E¹ are preferably $\frac{1}{12}$ inch ($\frac{1}{2}$ em) apart to conform to the usual length graduations for typographical lines. When the mold slot is adjusted longitudinally as above explained, its thickness adjustment is not disturbed, the construction being such that the two adjustments must be independently made.

As means for adjusting the mold slot by points for thickness of slug, I provide the front wall of the mold cap with two groups of teeth G³ cut in opposing directions and stepped by points in inclined planes as shown. These teeth are engaged by a longitudinally movable thickness-adjusting member J which is banked against the bar D. In order to disengage the teeth J¹ on the member J from the teeth G³ on the mold cap, it is necessary to first press the mold cap down against the resistance of the spring H; the member J is thus freed for longitudinal movement and the direction of its movement relative to the inclined teeth G³ will determine a corresponding increased or decreased thickness for the mold cap and thus locks the member J in the selected position. Displacement of the member J in a forward direction is prevented by reason of a tongue J² thereon which enters a groove D⁴ in the bar D. When the adjustment for thickness takes place the left-hand end-closing member I remains immovable by reason of the fact that its central portion I² fills the space

between the mold base A and the inner edge B⁵ of the web B, while its front edge I¹ clears in the recess G² of the mold cap. But the right-hand end-closing member K of the mold moves with the mold cap during the adjustment for thickness, and to this end is provided with an undercut projection K¹ which hooks over the lip G⁴ of the mold cap and thus compels movement of the member K upwardly or downwardly with the mold cap. Longitudinal movement of the member K is prevented by reason of its position in a notch A⁶ in the mold base, and lateral displacement thereof is prevented by a web A⁷ in said notch which enters a channel K² in the member K. Spreading of the channel wall of the member K is prevented by means of a screw K³ which joins the two walls and clears in a slot A⁸ when the member K is moved. The left-hand end-closing member I is held against lateral displacement rearwardly by means of a key L seated in a recess in the mold base, the member K having a keyway I³ which is open at its outer end in order to permit the required longitudinal movement of the member I.

From the foregoing description it will be clear that when the mold is to be adjusted longitudinally the locking member E is lifted out of engagement with the teeth D² on the bar D, and when it is moved as permitted by the opening D⁴ the member J, mold cap G and left-hand closing member I move therewith, the mold cap sliding on the right-hand closing member K, and the left-hand member I sliding on the mold base A. Hence so far as longitudinal adjustment is concerned these two sliding contacts are the parts to be kept lubricated in order to resist any tendency of the molten metal to enter between the contacting surfaces and to permit the sliding parts to be easily moved; also, to the extent that the parts slide one upon the other, the floor and roof of the mold slot are lubricated, and the slug is more readily ejected by reason of this occasional lubrication. Likewise, when the mold cap is pressed downward and returned when adjusting the mold slot for thickness, the parts to be lubricated are the concealed surfaces of the right-hand end-closing member K and the joint between the inner end of the left-hand member I and the end of the mold cap G. In order that all of these sliding parts may be automatically lubricated from time to time as they are adjusted and as the mold carrier is rotated, I provide as follows:

Associated with each mold is a lubricant cell or reservoir M in communication with a duct N which in turn communicates with a duct O leading from an annular groove P in the carrier stud Q to an opening in the edge A⁹ of the raised central portion of the mold carrier. The lubricant is poured into

any one of the openings O^1 when in an upper position as determined by the rotation of the carrier, and flows through the annular groove P and thence through the ducts 5 O and N into the cells M . By reversing the carrier all of the ducts and cells may be thus filled from time to time, but when once filled all of the molds will be kept lubricated until the lubricant is entirely consumed. This 10 is because the lubricant flows around the stud Q from one to another of the molds as the disk is rotated while in use. But since the mold in use occupies the upper position a greater part of the time of such use, it 15 will receive less lubrication than the other molds, and this is desirable because of the fact that the operative mold becomes heated and the oil would have a tendency to escape in undue quantity if the cell M associated 20 therewith remained filled with lubricant. The entire quantity of oil may be such that it will not flow so far as the operative mold as the carrier rotates during normal operation of the machine in which it is mounted. 25 When in a position of rest and while the slug is being ejected, the operative mold is in vertical position at the right-hand side of the carrier, hence receives no additional supply of lubricant. A valve O^2 serves to 30 open and close the entrance of each duct O^2 when supplying lubricant through the opening O^1 . From the cell M the lubricant enters an opening L^1 through the key L , and as the end-closing member I is moved from 35 time to time a modicum of lubricant enters an opening I^4 through the center thereof and is distributed on the contacting inner edge B^5 of the flange B and thence to the joint between the mold cap G and end member I . Also, a necessary quantity of lubricant escapes around the key L , through the groove A^1 and an opening A^{10} to the surface of the end-closing member K and thence into the center channel K^2 thereof, and from 40 this channel it may pass through an opening K^4 and lubricate the under side of the mold cap.

Having thus described the construction of my invention, its advantages, and mode of 45 operation, what I claim as new and desire to secure by Letters Patent, is:

1. In a rotatable mold-carrier having molds arranged in multiple about the center of rotation thereof for selective use, means 50 for insuring uniform and accurate spacing of said molds from the center of said carrier, said means comprising a base common to all of said molds and forming the center portion of said carrier.

2. A rotatable mold-carrier, having a central portion with integral edges each of which are equidistant from the center of rotation of said carrier and each of which serves as a casting-floor for one of the molds 55 on said carrier.

3. In a rotatable mold-carrier having a central portion the edges of which serve as casting surfaces for molds, means for lubricating said casting surfaces intermittently as said carrier is rotated, said means being 70 lubricant ducts leading from said casting surfaces and communicating one with another in order that a common supply of lubricant will flow from one to another of said casting surfaces as said carrier is rotated. 75

4. A structure as specified in claim 3 including also adjustable mold-elements in engagement with the casting surfaces therein recited, and the specified means whereby said adjustable mold-elements are supplied with 80 lubricant from said lubricant ducts.

5. In a rotatable mold-carrier having adjustable molds arranged about the center thereof for selective use, means for lubricating the surfaces of said molds from a common supply of lubricant, said means consisting of a system of communicating lubricant ducts leading from one to another of said molds and to an adjustable element thereof, and said adjustable element serving to transfer a film of said lubricant to other portions of said mold when it is adjusted relative thereto. 90

6. In an adjustable mold, a rotatable disc-carrier therefor having an internal flange secured to a central and relatively thicker portion of said carrier, a mold cap having a longitudinal channel occupied by the inner edge of said flange, means for adjusting said channeled cap longitudinally on said flange 95 for determining the length of the casting slot of said mold, means for adjusting said channeled cap transversely for determining the thickness of said casting slot, an end wall for said slot movable longitudinally with said cap in determining the length of said slot, and an opposed end wall movable transversely with said cap in determining the thickness of said slot. 100

7. In an adjustable mold mounted on a rotatable carrier, a central portion A for said carrier forming a base for said mold, an internal flange B secured to opposite ends of said central portion, an end wall I for said mold guided and adjustable longitudinally 110 between said base and said flange, a channeled mold cap G having its front wall recessed to engage said end wall for longitudinal movement therewith and having its channel occupied by said flange for guidance thereon, an opposed end-wall K having a channel K^2 occupied by a web A^7 in a notch A^6 of said base for transverse guidance thereon and therein respectively, an engagement K^1 between said opposed end wall and said mold cap permitting said cap to be moved longitudinally relative to said wall, but transversely therewith; a banked adjusting element J movable longitudinally relative to inclined rows of teeth G^3 on the front 120

125 of said carrier. 130

wall of said channeled cap to establish the transverse adjustment of said mold cap and said opposed end-wall K, a spring H on said cap for retaining said cap and end wall in their adjusted position, a banking element D for resisting said spring; and means for adjusting said mold cap G and said first-recited end-wall I longitudinally, said means em-

bodying a locking element E keyed to said mold cap through an opening B⁴ in said flange and adjustable on said banking element D against the resistance of said spring H.

Signed at Pasadena, Los Angeles County, California, this 19th day of October, 1926.

GEORGE E. MARLATT.
